F. H. PIERPONT

MATRIX CASE EQUIPMENT FOR TYPE CASTING MACHINES

Filed June 21, 1923

Fig. 4.

INVENTOR:
Frank Hinman Pierpont,
BY John A. Ferguson
HIS ATTORNEY.

UNITED STATES PATENT OFFICE.

FRANK HINMAN PIERPONT, OF SALFORDS, HORLEY, ENGLAND, ASSIGNOR TO LANSTON MONOTYPE MACHINE COMPANY, OF PHILADELPHIA, PENNSYLVANIA, A CORPORATION OF VIRGINIA.

MATRIX-CASE EQUIPMENT FOR TYPECASTING MACHINES.

Application filed June 21, 1923. Serial No. 646,980.

To all whom it may concern:

Be it known that I, FRANK HINMAN PIERPONT, a citizen of the United States of America, residing at Salfords, Horley, in the county of Surrey, England, have invented certain new and useful Improvements in Matrix-Case Equipments for Typecasting Machines; and I do hereby declare the following to be a full, clear, and exact description of the same, reference being had to the accompanying drawings, forming part of this specification, and to the characters of reference marked thereon.

This invention relates to die case or matrix case equipment for typecasting machines and refers more particularly to die cases wherein matrices, arranged in columns and rows, are supported in such a manner as to limit the motion of the individual matrices laterally, as described for example, in the specification of United States Letters Patent No. 784,245, dated March 7, 1905.

Matrix case equipment of this kind comprises oblong matrix blocks, rectangular in cross section and provided with a character cavity in one end and a conical centering cavity or cone hole in the opposite end for engagement by a centering device by which each matrix is pressed or clamped against the mold when a cast is to be made. The centering device and mold are parts of a typographic casting machine well known in the art as manufactured by Lanston Monotype Machine Company, such machine being basically represented in United States Letters Patent No. 625,998, dated May 30, 1899. The patented matrices are provided with transverse grooves on their four side walls within which grooves, when the matrices are assembled in their case, extend parallel supporting bars and teeth projecting from the bars at right angles thereto, all in a manner disclosed in the patent and well understood by those skilled in the art.

The principal object of the present invention is to provide a matrix case equipment suitable for use in a typographic machine of the kind referred to, in which the ma-

trices are provided with large wearing surfaces, the suspension devices comprise separate series of parallel bars one being at right angles to the other and the case is formed to support these bars and matrices, the whole being of great simplicity in structure and assembly and inexpensive to manufacture.

In accordance with the present invention, the matrices are supported by or suspended on, a series of parallel bars preferably rectangular in cross section, for the reception of which each matrix is provided in two of its opposite side walls with external transverse grooves, these bars limiting the movement of the individual matrices in one direction. The matrices are also suspended by or supported on, a series of parallel rods preferably circular in cross section arranged at right angles to the suspension bars and for the reception of these bars, each matrix is provided with a central hole or opening and these rods which limit the movements of the individual matrices in another lateral direction, pass through openings in the suspension bars, so that the rods and bars interlock.

Since the matrices have only grooves in two walls and have two entire walls ungrooved, a large and well distributed bearing surface is provided and the suspension bars and rods, which are supported at their ends in suitable bearings in the frame of the die case, interlock with one another, and provide rigid supports for the matrices.

Referring to the accompanying drawings:

Fig. 1 is an inverted plan of a die case incorporating the present invention.

Fig. 2 is a section on the line 2—2 of Fig. 1.

Fig. 3 is a section on the line 3—3 of Fig. 1, and,

Fig. 4 is a perspective view of a matrix.

The matrices are represented by the character 5, the suspension bars by the character 6 and the suspension rods by the character 7.

The die case 8 as hitherto comprises a

frame having an opening to accommodate a font or arrangement of matrices. It is provided with means of supporting it in the typographic machine and for coupling it with translating or positioning devices thereof. On the rear or top side is the usual cover plate or matrix protector 9.

Along two of the opposite sides of the die case the walls surrounding the matrix receiving space, are each provided with a series of slots or grooves 10 to receive the parallel suspension bars 6, (see Figs. 1 and 2), and in the two remaining walls are formed openings or holes 11 for the reception of the ends of the cylindrical suspension rods 7. The holes 11 in one wall are of practically the same diameter throughout as the suspension rods and extend through the wall so that the rods can be inserted through them from the exterior of the die case. The holes 11 in the opposite wall are, at their inner ends of the same diameter as the suspension rods but this diameter is not continued to the outside of the wall so that shoulders 12 are formed which constitute stops for the ends of the rods. The holes are continued of smaller diameter to the outside of the walls to permit of the insertion of a wire or the like for pushing the suspension rods out. The rods are held in place by a plate 13, the ends of which rest in slots 14 in the die case frame.

The matrices 5 are formed on two of their exterior walls with transverse grooves 15 (see Figs. 3 and 4) of a depth equal to approximately half the thickness of a suspension bar and a little wider than a suspension bar 6; the remaining side walls of the matrix are plain. At right angles to the grooves 15 each matrix has a central hole or opening 16 of slightly larger diameter than the suspension rods 7.

The suspension bars are each furnished with a series of holes 17 for the passage of the suspension rods 7.

The suspension bars 6 are placed between rows of matrices 5 before the latter are placed in the die case and when the bars 6 and matrices 5 are placed in the die case the ends of the bars 6 rest in the slots 10 in the walls of the die case and prevent or limit the movement of the matrices in one direction. After the matrices 5 and bars 6 have been placed in the die case, the suspension rods 7 are inserted so that they pass through the holes 17 in the bars 6 and the central holes 16 in the matrices 5 and prevent or limit the movement of the individual matrices in a direction at right angles to the direction controlled by the bars 6.

By means of the bars 6 and rods 7 each matrix is individually supported and lateral movement in both directions is limited or prevented.

The sides of the matrices which have the

grooves 15 have portions 18 of the original walls left at the upper and lower ends of the matrices and these portions serve as bearing surfaces to prevent or minimize the tendency of the matrices to turn or tilt. The remaining two walls 19 of the matrices have the entire original surface left to form bearing surfaces for the same purpose. Thus larger and better distributed bearing surfaces are provided than with matrices as hitherto constructed.

Should the bearing surfaces formed by the walls of the matrices wear, further turning or tilting will be prevented by the suspension bars 6 and the suspension rods 7.

The rods 7 and bars 6 interlock and form rigid supports for the individual matrices throughout the die case, thus reducing wear between the matrices. It will also be noted that the rods consist of round stock merely, that the bars are simple flat plates, rectangular in cross section, with holes drilled through them and that the matrices are also easy and inexpensive to manufacture.

I claim:

1. A die case equipment comprising a series of parallel bars, a series of parallel rods arranged at right angles to the bars and passing through openings therein and a series of matrices each provided on two opposite sides with grooves to receive the bars and with a central transverse opening to receive one of the rods said matrices being supported by both bars and rods.

2. In a die case equipment the combination with an open frame, of a series of parallel suspension rods mounted in openings in the side of the frame, and being capable of being withdrawn by an endwise movement, a series of parallel suspension bars arranged at right angles to the rods and supported in slots or recesses in the frame of the die case and a series of matrices each provided with transverse grooves and a central hole, said matrices being suspended and supported on the bars by said transverse grooves and on the rods by said central holes.

3. In a die case equipment, a series of parallel suspension rods and a series of parallel suspension bars arranged at right angles to the rods and interlocking therewith to form matrix supporting cells.

4. In a die case equipment a frame, a series of detachable suspension rods and a series of detachable suspension bars at right angles to the rods, each bar being formed with a series of openings for the passage of the suspension rods and the bars and rods forming matrix supporting cells.

5. In a die case or holder, the combination with a pair of suspension bars provided with openings, a matrix externally grooved to be mounted on the bars, said matrix being also provided with a central opening, of an associated rod adapted to pass through said

openings in the bars and through said opening in the matrix and a frame in which the bars and rod are mounted, whereby the matrix is supported in the frame by both 5 bars and rod.

6. A typographic matrix comprising a rectangular block furnished on two opposite

sides with transverse side bearing grooves for the accommodation of supporting bars and with a central transverse opening for 10 the accommodation of a supporting rod, said opening being at right angles to the side grooves, the two remaining sides being plain.

FRANK HINMAN PIERPONT.
